ADJUSTABLE SOFA BED HAVING SHIFTABLE
FRONT BOARDLouis Pokorny and Louis Pokorny, Jr.,
Ronkonkoma, N. Y.

Application September 17, 1948, Serial No. 49,716

4 Claims. (Cl. 5-13)

1

Our present invention relates generally to articles of furniture and has particular reference to an adjustable structure which in its closed position forms a sofa and which may be adjusted into an open position in which it defines a bed. A structure of this kind is illustrated and described in our patent, No. 2,445,241, issued July 13, 1948.

It is a general object of the present invention to provide an improved mechanism for adjusting the frontboard of the device during the transformation of the structure from a sofa to a bed. Devices of this general type usually have a frontboard extending across the front of the sofa and provided with a padded upper edge. In the closed condition of the device, the top surface of this pad is substantially flush with the uppermost part of the folded bed spring, so that a level support is afforded for the seat cushions of the sofa. However, in the open condition of the device, the upper edge of the frontboard is likely to present an uncomfortable obstacle to a person reclining on the bed, and it is therefore necessary to move the frontboard during the opening of the device.

In accordance with the present invention, the frontboard is shifted automatically from a raised to a lowered position as the frame is adjusted from a folded, sofa position to an unfolded, bed position. The shifting of the frontboard is accomplished by a mechanism which is automatically actuated as the frame is folded and unfolded; and the movement of the frontboard is one which shifts the board through a relatively short distance and maintains it, at both extremes of its movement, in a vertically-disposed bracing relation to the middle legs of the structure.

One way of achieving the foregoing objects, and such other objects as may hereinafter appear or be pointed out, is shown in the preferred embodiment of our invention illustrated in the accompanying drawings, in which:

Fig. 1 is a transverse sectional view through the device in closed position;

Fig. 2 is a similar sectional view of only certain sections of the frame, this figure showing an intermediate stage in opening the device from its closed position (Fig. 1);

Fig. 3 is likewise a sectional view, but showing the sections of Fig. 2 when the device is fully opened to define a bed;

Fig. 4 is a transverse section taken substantially on the line 4-4 of Fig. 3, at a point just in front of the frontboard; and

2

Fig. 5 is an enlarged detail section, taken substantially on the line 5-5 of Fig. 3.

Before entering upon a description of the present invention, the device as a whole will be briefly described. The device is shown in Fig. 1 in its closed position defining a sofa represented in dot-and-dash lines, having a back 9. When fully open (see Fig. 3 and also Fig. 5 of our earlier patent), the device defines a bed, the frame of which is made up of four sections. When the frame is in closed position, as in Fig. 1, these four sections assume dispositions different from their horizontal dispositions when opened out to form the bed; for facility in terminology, the four sections will be given descriptive appellations based upon their respective dispositions in closed position, Fig. 1. Thus, section 10, which is nearest the back 9 of the sofa and is vertical, will be referred to as the "rear vertical section"; section 20 which is horizontal and lower (compared with section 40, which is also horizontal) will be referred to as the "lower horizontal section"; section 40 will be termed the "upper horizontal section"; and section 30, which is vertical (like section 10) but which is at the front of the sofa, will be referred to as the "front vertical section."

The three sections 20, 30 and 40 are straight-line members, while rear vertical section 10 is angular, having an arm 15 pivotally articulated at 16 to a short vertical bar 6 secured to the frame of the sofa. The lower end of rear vertical section 10 is articulated, at 12, to the rear end of the lower horizontal section 20. The forward end of section 20 is articulated, at 23, to the lower end of front vertical section 30, the upper end of which is articulated, at 34, to the front end of upper horizontal section 40.

The parts 10, 20, 30, 40 have been spoken of as "sections" rather than mere members because each section 10, 20, 30, 40 has a companion part or member at the respective right and left ends of the sofa. The particular sections 10, 20, 30, 40 shown in Figs. 1, 2 and 3 represent only the companion parts at one end of the sofa (the left end as viewed in Fig. 4). The corresponding parts of the sections at the opposite end of the sofa are not shown except in Fig. 4 where the second part of section 30 is designated 30'. The elements forming the sections 10, 20, 30, 40 are angle irons, as indicated most clearly at 30 and 30' in Fig. 4.

The device includes a pair of middle legs, one associated with each set of members at the left and right of the sofa. The leg associated with

members 10, 20, 30, 40 is designated 50. In Fig. 4, the corresponding leg at the opposite end of the sofa is designated 50'.

Middle leg 50 is a plate or casting of somewhat irregular shape and is articulated at its upper portion, at 35, to a short arm 33 rigidly secured to section 30 and projecting from it. The corresponding leg 50' is articulated at 35' to arm 33' of companion section 30'. A frontboard 51 extends across the sofa and is articulated to the middle legs 50, 50' in a manner presently to be described.

The device is opened by lifting the frontboard 51 and pulling it upwardly and away from the sofa. This causes a turning of rear section 10 about fixed pivot 16 and brings about a raising of the lower horizontal section 20 (and also the other sections 30 and 40 and middle leg 50). (The relationship of the parts in this first stage is best shown in Fig. 3 of our earlier patent.) This raising of section 20 is assisted by an elevator arm 22, pivoted to section 20 at 21 and provided with a short lever arm 26 whose free end is secured to an elevator tensile spring 2.

The device is then further opened by turning front vertical section 30 about the pivotal connection 23 from the vertical position of 30, Fig. 1, to its horizontal position, Fig. 2, in alignment with lower horizontal section 20; and by turning upper horizontal section 40 through 180° to bring it from the sofa position of Fig. 1 through the intermediate position of Fig. 2 to the bed position of Fig. 3.

In the closed condition of the device, Fig. 1, the middle leg 50 is parallel and close to the front vertical section 30, and lies between this section and the frontboard 51. In the fully open condition of the device, Fig. 3, the middle leg 50 is perpendicular to front vertical section 30, the leg having been turned 90° relative to section 30 about its pivotal connection 35. This 90° turning of leg 50 is automatically achieved by means of three members 28, 48, 58, two of which (28 and 48) constitute toggle links articulated together at 24. Toggle link 28 is the rear toggle link and is pivotally connected, at 29, to section 20. The front toggle link 48 is articulated at 49 to the section 40. The member 58 is an actuating member or lever, pivotally connected to rear toggle 28 at 57 and pivoted at 59 to middle leg 50. As the frame as a whole is unfolded, toggle links 28, 48 open up, and member 58 causes the leg 50 to turn relative to front vertical section 30.

In the unfolded condition of the frame, the section 40, Fig. 3, is supported by a front leg 43 pivotally connected to it at 42 and actuated by a link 46.

The device has a bed spring 1, Fig. 4, which is secured at its edges to the sections 10, 20, 30, 40. In Fig. 4 the spring 1 is shown connected to the elements 30, 30' by means of tensile springs 3. A cross-bar 17 may be spanned between the left and right sets of the sections, as shown in Fig. 4, and in order that the cross piece 17 will not present an objectionable abutment to a body reposed on the bed spring 1, it is offset downwardly, as at 18, 18'.

The padding of the upper edge of the frontboard 51 is achieved by means of a soft rubbery resilient body 53 which rests on a board 52 of short width extending rearwardly from frontboard 51 to which it is secured. To accommodate the board 52 and pad 53, frontboard 51 is provided with a recess 51* (see Fig. 4). This

recess extends downwardly from the upper edge of the frontboard 51 and extends for almost the full length of the frontboard.

In the closed position of the sofa, Fig. 1, the padding 53 presents a support, at the front of the sofa, for the seat pillows 5 and the weight of a person seated thereon. It will be noted that the top surface of padding 53 is substantially flush with the horizontal legs of the angle irons constituting the upper horizontal section 40, 40', and with the bed spring which is connected to these flanges. When the device is opened out to form a bed, Fig. 3, the frontboard 51 is shifted to a lower position where its upper edge will offer no obstacle to a body reposed on the bed spring. This is shown most clearly in Fig. 4, in which it will be noted that the padding 53 lies well below the level of the bed spring 1.

By means of the present invention we achieve the lowering and raising of frontboard 51 in a unique fashion which has numerous advantages. The board is shifted endwise, i. e., parallel to itself, through a relatively short distance; it is maintained in parallel abutment with the legs 50, 50' in each of its raised and lowered positions and thus stiffens and braces the entire structure; and the movements of the board are automatically achieved by a simple parallel-motion mechanism which is actuated by the leg-turning member 52.

For these purposes, frontboard 51 is secured to the flanges 54a (see Fig. 4) of a pair of short angle brackets 54, 54' adjacent to the middle legs 50, 50' respectively. The other flanges of these brackets are designated 54b. The member 53 is a lever whose fulcrum is at 59 and whose short arm 56 is pivotally connected, at 55, to the flange 54b of angle 54. Short arm 56 is thus a short extension of actuating member 58 projecting forwardly into pivoted engagement with the frontboard 51. A second arm 66 of the same length as arm 56 is pivotally mounted at 69 to middle leg 50 and articulated to angle bracket 54 at 65. Arms 56, 66 constitute a parallel-link motion, which serve to raise and lower frontboard 51 relative to the middle legs 50, 50', as follows: In the closed condition of the device (Fig. 1) rear toggle link 28 is inclined rearwardly (leftwardly in said figure), pulling member 58 in that direction, thus forcing arm 56 upwardly. This upward movement of arm 56, and of its parallel companion arm 66, maintains the frontboard 51 in its raised position, in firm contact with the legs 50, 50'. As the device is opened to form a bed (Figs. 2 and 3) lever 58 turns relative to the leg 50, thus lowering its short arm 56. The lowering of short arm 56, and of its parallel companion arm 66, moves the frontboard 51 to its lowered position, as shown in Figs. 3 and 4, again in firm contact with the legs 50, 50'. The frontboard is thus effective to brace the pair of middle legs in both the closed and the open positions.

The frontboard 51 is covered with a piece of upholstery fabric 11 which also extends over the top of pad 53. At 7* this fabric is stitched or otherwise secured to an extension 7 (which may be of less expensive material). This extension is secured to cross-member 41 of upper horizontal section 40 by means of springs 8. In the closed position of the frame, the extension 7 overlies the section 40 and the bed spring; while in the open position of the frame, the fabric 11 assumes the position shown in Fig. 3.

The connection of the fabric 11 directly to the

fabric 11 has the advantage of covering over and closing the gap between the pad 53 and the frame itself when the frame is in sofa-defining position (Fig. 1). This advantage is the direct result of the present improved mechanism which shifts the frontboard only through a slight distance and keeps it in vertical disposition in both the closed and opened conditions of the frame.

In general, it will be understood that those skilled in the art may readily make changes in the details herein described and illustrated without necessarily departing from the spirit and scope of the invention as expressed in the appended claims.

Having thus described our invention and illustrated its use, what we claim as new and desire to secure by Letters Patent is:

1. In a sofa-bed, a frame foldable to define a sofa and unfoldable to define a bed, said frame comprising companion members at each side constituting sections, said sections including an upper horizontal section which defines the seat of the sofa when the frame is folded and a front vertical section which swings to a horizontal position when the frame is unfolded, a frontboard having a padded upper edge substantially aligned with said upper horizontal section when the frame is folded, an upholstery covering on said frontboard and over said padding, means for moving said frontboard to a lowered vertical position beneath said front vertical section when the frame is unfolded, and an extension on said upholstery whose free end is secured to the free end of said upper horizontal section, said extension overlying said upper horizontal section when the frame is folded and underlying said section when the frame is unfolded.

2. In a sofa-bed, a frame foldable to define a sofa and unfoldable to define a bed, said frame comprising companion members at each side constituting sections, one of said sections being a front vertical section which swings to a horizontal position when the frame is unfolded, a frontboard, and means for moving said frontboard between a raised vertical position in front of said section when the frame is folded and a lowered vertical position beneath said section when the frame is unfolded, said means including a leg pivoted to said section and lying between said section and said frontboard when the frame is folded, and an actuating member pivoted to said leg and having a short extension projecting forwardly from said leg and pivoted to said frontboard.

3. In a sofa-bed, a frame foldable to define a sofa and unfoldable to define a bed, said frame

comprising companion members at each side constituting sections, one of said sections being a front vertical section which swings to a horizontal position when the frame is unfolded, a frontboard, and means for moving said frontboard between a raised vertical position in front of said section when the frame is folded and a lowered vertical position beneath said section when the frame is unfolded, said means comprising a leg pivoted to said section and lying between said section and said frontboard when the frame is folded, an actuating member pivoted to said leg and having a short extension projecting forwardly from said leg and pivoted to said frontboard, and a link parallel to said extension and pivoted to the leg at one end and to the frontboard at the other.

4. In a sofa-bed, a frame foldable to define a sofa and unfoldable to define a bed, said frame comprising companion members at each side constituting pivotally connected sections, said sections including a lower horizontal section, an upper horizontal section, and a front vertical section which swings to a horizontal position when the frame is unfolded, a frontboard, and means for moving said frontboard between a raised vertical position in front of said front vertical section when the frame is folded and a lowered vertical position beneath said section when the frame is unfolded, said means comprising a leg pivoted to said front vertical section, a pair of toggle links between said lower and upper horizontal sections, said toggle links opening up when the frame is unfolded, a leg-turning member pivoted at its rear end to one of said toggle links and near its forward end to said leg, said member having a short forward extension pivoted to said frontboard, and a link parallel to said extension and pivoted to the leg at one end and to the frontboard at the other.
